CENTRIFUGAL CASTING

Frank G. Carrington, Anniston, Ala., assignor to
 Centrifugal Pipe Corporation, Jersey City, N. J.,
 a corporation of Delaware

Application February 18, 1933, Serial No. 657,376

4 Claims. (Cl. 22—79)

This invention relates to improvements in machines for centrifugally casting metal, and has for its object improvements in the reservoir or ladle from which molten metal is poured into the mold feeding trough, and in the mechanism for actuating that ladle.

Centrifugal casting machines of the so-called de Lavaud or spout type are commonly provided with a tilting ladle pivotally mounted on a standard above and behind the pouring trough. During the casting operation this ladle is slowly tilted, discharging a continuous stream of molten metal into an inclined runner from which it flows into the trough and thence into the receding rotating mold, the tilting of the ladle being synchronized with the mold traverse. Metal sufficient for one casting is supplied to the pouring ladle from a larger supply ladle which is carried from machine to machine usually by an overhead crane. In a plant in which a battery of casting machines are in operation, production may be slowed up by the inability of the supply ladle to make its rounds speedily enough.

In order to overcome this difficulty I provide each machine with a pouring ladle of sufficient size to hold enough metal to cast more than one pipe, usually two. Thus after one pipe has been cast another may be cast immediately thereafter without awaiting the return of the supply ladle. If, however, the pouring ladle is permitted to swing back under its own weight into its original position, as is the present practice, it becomes necessary to tilt it through half its total pouring arc before the metal reaches the pouring lip for the second casting. As the ladle elevating mechanism is geared for a slow tilting motion synchronized with the mold traverse this means a loss of the time of one casting operation. If, on the other hand, the pouring ladle is tilted half way for the first pipe and then held in half-elevated position some of the metal will surge forward over the pouring lip and continue to trickle into the trough until the metal in the ladle comes to equilibrium. This metal trickling into the trough after the casting is complete freezes there and must be removed before the next casting operation, otherwise it will be carried into the mold as solid particles and result in defective castings.

In accordance with the present invention I provide means whereby when the power tilting the pouring ladle is cut off after the first casting, the ladle automatically drops back through an arc large enough to prevent surging or accidental spilling of the metal over the pouring lip, but not large enough to delay materially the second cast-

ing operation. The second tilting begins with the ladle only slightly lowered from its position at the termination of the first casting.

In the accompanying drawing I have illustrated a preferred embodiment of my invention. In this drawing Figure 1 is a side elevation showing more or less diagrammatically a centrifugal pipe casting machine of the de Lavaud type and illustrating the improved ladle-tilting mechanism of my invention; Figure 2 is a plan view, on an enlarged scale, of the ladle-tilting mechanism; Figure 3 is a vertical section taken along line 3—3 of Figure 2 and Figure 4 is an end view of the mechanism shown in Figures 2 and 3.

The centrifugal casting machine illustrated in Figure 1 comprises the usual mold 1 designed to be traversed longitudinally with reference to a pouring trough 2. Mounted on a standard 3 above and to the left of the trough 2 is a tilting pouring ladle 4 which is tilted during casting to pour a stream of molten metal down runner 5 into the trough 2 and thence into the mold. The foregoing is a common construction and, of itself, forms no part of the present invention.

I shall now describe the mechanism for tilting the pouring ladle with particular reference to Figures 2, 3 and 4. A vertical connecting rod 6 is pivotally connected at its upper end to the ladle 4 and at its lower end to a pivoted segment 7, so that as the segment 7 is swung about its pivot the ladle 4 is correspondingly swung about its pivot. The segment 7 is actuated by a motor 8 driving a pinion 9 meshing with teeth 11 on the periphery of the segment.

I shall now describe the mechanism for holding the ladle in elevated position at the termination of the first casting operation. The segment 7 carries on one face a ratchet 12 which is engaged by a pawl 13 pivoted at one end of arm 14, pivoted at 15 and carrying counterweight 16, this counterweight urging the arm 14 into the position illustrated in Figure 3. During the upward or clockwise movement of the segment 7 the pawl 13 slides over the ratchet. Upon reversal of this movement, however, the pawl engages the adjacent ratchet tooth and holds the segment against return movement. The arm 14, however, is free to swing through a small arc until it engages a stop 17.

In the casting of pipe centrifugally in the machine just described the ladle 4 is filled from the supply ladle with sufficient metal for, let us say, two pipes. The mold is retracted to cover the pouring trough and when everything is in readiness the motor switch is closed and the segment

7, acting through connecting rod 6, slowly tilts the ladle and the pipe is cast in the usual way. At the termination of the first casting operation the ladle has been elevated only half way and is still half filled with molten metal. At this point the operator opens the motor switch and were it not for the ratchet 12 and pawl 13 the ladle would swing backward to its original position. As soon, however, as this downward movement begins the pawl 13 engages the nearest tooth on the ratchet 12, and the segment and the ladle swing back through the small arc defined by the angle between arm 14 and its stop 17. When the arm 14 engages stop 17, further downward movement is arrested. The parts will then remain in this position until the time comes for the second casting whereupon the operator closes the motor switch and elevation of the ladle 4 is resumed.

20 At the termination of the second casting operation the ladle would also be held in an elevated position, so in order to return it for refilling I provide a plunger 18, mounted in a cylinder 19, which plunger is actuated to strike the pawl 13 disengaging it from the ratchet and permitting the ladle 4 and segment 7 to swing back under their own weight.

I claim:

1. In a centrifugal casting machine, a pouring ladle capable of holding a charge of molten metal sufficient for a plurality of castings, means for tilting the ladle to discharge the metal, a ratchet coupled to said ladle, a pawl engaging the ratchet and preventing return of the ladle when the tilting means cease to operate, and means whereby a slight downward movement of the pawl at the termination of the first casting operation is secured, thereby lowering the level of the residual metal but holding the ladle in elevated position.
- 20 2. In a centrifugal casting machine, a pouring ladle capable of holding a charge of molten metal

sufficient for a plurality of castings, means for tilting the ladle to discharge the metal, a ratchet coupled to the ladle, a pawl engaging the ratchet and preventing return of the ladle when the tilting means cease to operate, means whereby a slight downward movement of the pawl at the termination of the first casting operation is secured, thereby lowering the level of the residual metal but holding the ladle in elevated position and means for disengaging the pawl at the termination of a subsequent casting operation thereby permitting the ladle to return to its original position.

3. In a centrifugal casting machine, a pouring ladle capable of holding a charge of molten metal sufficient for a plurality of castings, means for tilting the ladle to discharge the metal, a ratchet coupled to the ladle, a pivoted counterweighted pawl engaging the ratchet and preventing return of the ladle when the tilting means cease to operate and a stop permitting a slight downward movement of the pawl at the termination of the first casting operation thereby lowering the level of the residual metal but holding the ladle in elevated position.

4. In a centrifugal casting machine, a pouring ladle capable of holding a charge of molten metal sufficient for a plurality of castings, means for tilting the ladle to discharge the metal, a ratchet coupled to the ladle, a pawl engaging the ratchet and preventing return of the ladle when the tilting means cease to operate, means whereby a slight downward movement of the pawl at the termination of the first casting operation is secured thereby lowering the level of the residual metal but holding the ladle in elevated position, and a plunger for disengaging the pawl at the termination of a subsequent casting operation thereby permitting the ladle to return to its original position.

FRANK G. CARRINGTON.
